DESIGN FOR A GRIDDLE

George T. Raiser, Los Angeles, Calif.

Application February 23, 1942, Serial No. 105,950

Term of patent 7 years

To all whom it may concern:

Be it known that I, George T. Raiser, a citizen of the United States of America, residing at Los Angeles, in the county of Los Angeles, State of California, have invented a new, original, and ornamental Design for a Griddle, of which the following is a specification, reference being had to the accompanying drawing, forming a part thereof.

Fig. 1 is a front elevational view of the griddle, showing my new design;

Fig. 2 is a front elevational view with the griddle open showing the inside of the upper member, the lower member having the same design on its inside face;

Fig. 3 is a top plan view of the griddle in closed position, and

Fig. 4 is an end elevational view of the griddle in closed position.

I claim:

The ornamental design for a griddle, as shown and described.

GEORGE T. RAISER.
